UNITED STATES PATENT OFFICE.

PEDER WIGGEN, OF CHICAGO, ILLINOIS, ASSIGNOR OF ONE-HALF TO OSCAR NELSON, OF CHICAGO, ILLINOIS.

PNEUMATIC MUSICAL INSTRUMENT.

1,136,190.

Specification of Letters Patent. Patented Apr. 20, 1915.

Application filed February 10, 1913. Serial No. 747,458.

To all whom it may concern:

Be it known that I, PEDER WIGGEN, a citizen of the United States of America, residing at Chicago, in the county of Cook and State of Illinois, have invented certain new and useful Improvements in Pneumatic Musical Instruments, of which the following is a specification.

My invention has relation to self-playing musical instruments or to that class of instruments known to the trade as "orchestrons," and comprises a number of different and well-known instruments, such as a piano, a plurality of flutes, and violin note-producing tubes, a snare drum, a tri-angle, a cymbal, a base and a tympany drum, all of which are played upon independently or collectively through the agency of air currents from main or power pneumatics, and controlled by quick-acting valves which are, in turn, controlled by a perforated note sheet passing over a "tracker bar," such as are commonly used in instruments of this character.

In the present embodiment of my invention, certain of the different instruments are actuated by a suction of air, while others are actuated by a blowing pressure, and the principal object of my invention resides in providing a main suction chamber arranged horizontally within the main casing of the instrument and detachably secured thereto, to which chamber all of the suction actuated instruments and their controlling mechanisms are mounted, whereby said chamber will serve as a support for these parts, and also permit the same to be placed within or removed from the main casing of the instrument as a unit, thus saving the necessity of assembling or disassembling each part separately within the casing.

Further objects of my invention reside in providing automatically controlled means for softening the tone of the various instruments uniformly; in providing cut-off devices whereby, the playing of certain of the different instruments may be readily discontinued whenever desired, and in arranging the various parts of my invention so that they are all accessible and may easily be reached for the purpose of repairs or adjustments when needed.

Other objects and their resultant advantages will become apparent as the nature of my invention becomes better understood

from the following description and accompanying drawings, in which latter—

Figure 1 is a face view of the upper portion of a piano case, showing the various parts of my invention in position therein; 60 Fig. 2 is a perspective view of the controlling chest for controlling the action of the pneumatic regulator; Fig. 3 is a plan view thereof looking into the chest from the rear; Fig. 4 is a vertical section taken along the line 4—4 of Fig. 3; Fig. 5 is a perspective view of the cut-off box; Fig. 6 is a top plan view of the cut-off box shown in Fig. 5 with the cover removed; Fig. 7 is a vertical section taken along line 7—7 of Fig. 6; Fig. 8 70 is a plan view showing the pneumatic and its controlling valves for playing the snare drum with the cover of the valve box removed; Fig. 9 is a vertical section taken along the line 9—9 of Fig. 8; Fig. 10 is a 75 face view of the parts shown in Figs. 8 and 9, and showing part of the drum; Fig. 11 is an enlarged vertical sectional view of the pneumatic and its valve for admitting air into the chamber which communicates with 80 the flute tubes; Fig. 12 is an enlarged vertical section through a portion of the main suction chamber and showing the means I employ for softening the tone of the various instruments; Fig. 13 is a side elevation of 85 parts shown in Fig. 12; Fig. 14 is a top plan view thereof; Fig. 15 is a sectional view taken through the main suction chamber and showing one of the pneumatics for playing the base drum and controlling valves; 90 Fig. 16 is an enlarged section taken along the line 16—16 of Fig. 1; Fig. 17 is a sectional view showing the valve chest and pneumatic for playing the tri-angle; Fig. 18 is a side elevation of the stand for supporting the cymbal; Fig. 19 is a partial horizontal sectional view taken along line 19—19 of Fig. 11 looking down; Fig. 20 is an elevation of the wind box located at one end of the main casing of the instrument with the 100 back cover removed; Fig. 21 is a sectional view thereof taken along the line 21—21 of Fig. 20; Fig. 22 is a top plan view of the intermediate or bleed valve box with the cover removed; Fig. 23 is a section there-through taken along the line 23—23; Fig. 24 is a section taken along the line 24—24 of Fig. 22; Fig. 25 is a diagrammatic view showing the various pneumatics and their connections; Fig. 26 is a detail showing the 110

operation of the shut-off valve of Fig. 15; and Fig. 27 is a horizontal sectional view through the controlling chest or box shown in Fig. 3.

5 Referring specifically to the drawings and the reference numerals indicated thereon: 1 denotes the main casing of the instrument, which may be arranged to resemble that of a piano, and within which is located a 10 snare drum 2, a triangle 3, a cymbal 4, and a drum 5, which, for the purpose of saving space, is provided with beaters which enables the drum 5 to be used as both a kettle and a base drum. Also arranged within the 15 main casing 1, and preferably below the instruments above referred to, are a series of graduated tubes 6, and immediately back of these tubes another series of tubes 7. The tubes 6 are so formed that when air is blown 20 thereinto they will sound flute-like notes, and will hereinafter be termed "flute-tubes", whereas tubes 7 are so formed as to sound a note similar to that of a violin, and will hereinafter be referred to as "violin-tubes".

All of the above mentioned parts may be of any standard construction of the various makes now on the market and will work equally as well with my invention.

30 Arranged horizontally between the end walls of the instrument casing 1 is the main suction channel 8, preferably rectangular in cross section and which is screwed to cleats 8^a at each end. A constant suction of air is 35 maintained throughout the channel 8, by means of a main vacuum pump or feeder (not shown) through passages to be herein-after referred to. Mounted upon the upper wall of the channel 8, near one of its 40 ends is a valve box 9, and into which air is admitted from channel 8, through openings 10 and 11 formed in the upper wall thereof on opposite sides of a transverse partition 12 (see Fig. 12). A bent wire lever 13 journaled in the end pieces of the valve box 9, carries thereon within the valve box a valve 14, at a point directly above the opening 10, and has one of its ends formed with an extension 14^a, and which is normally held 45 in a raised position by means of a spring 15, secured at one end to the extension 14^a, and at its other end to a block 16, fastened to the top of the valve box 9. The top wall of the box 9 also carries a pneumatic 17, pro- 50 vided with an arm 18, which arm is adapted to bear on the extension 14^a of the lever 13. Formed within the upper wall of the valve box 9, there is a port 19, which leads to the interior of the pneumatic 17, and to which 55 60 port is communicated a tube 20, in turn leading to a T-block 21, fastened to the underside of the channel 8, provided with ports 21^a and 22, the tube 20 communicating with the port 21^a. From port 22 a hose 65 or tube 23, leads to a port 25 formed in the

front wall of a controlling valve box 24, fastened also to the underside of the channel 8, and which port 25 normally communicates with the outside air. A vacuum is maintained within the controlling valve box 24, 70 through openings 26 and 27, formed in the valve box 24, and under wall of the suction channel 8, respectively. Fastened to the inner face of the front wall of the box 24 are pneumatics 28 and 29, having ports 30 75 leading from their interiors into the interior of the box 24. Also leading from the interior of the pneumatics 28 and 29 through the front wall of the box 24 are ports 31, from which hose 32 lead to a 80 tracker-bar or other pneumatic playing device (not shown), designed for operating musical instruments by admitting air to a passage for a period of time corresponding to that during which a desired note is to be 85 sounded.

A shifting lever 33, having its ends bent at right angles is carried by the front wall of the box 24 and is adapted to have its lower inner end extend between the pneumatics 28 and 29, and its upper outer end carries a valve block 34 having its inner face provided with a passageway 35, which is at all times in communication with a port 36, leading into the box 24, but leaves the 90 port 25 open to the outside air except when the lower end of the lever 33 is shifted by the pneumatic 28 being inflated or extended and the pneumatic 29 collapsed, in which event the valve block 34 will extend over 95 both the ports 36 and 25. In order to hold the valve block 34 in close contact with the box 24 and to compensate for wear, I interpose a coiled spring 37 between the valve 100 block and the shift lever 33.

Secured to the underside of the main suction channel 8, immediately below the valve box 9 is a pneumatic regulator 38, provided with openings 39 and 40, which register with similar openings 41 and 42 respectively formed in the under wall of the channel 8, and which are in alinement with the openings 10 and 11 above. Formed around the opening 39 is a valve seat 43, while the opposite leaf of the pneumatic 38 carries a 110 valve member 44 adapted to engage the seat 43 and close the port 39, in the event that the suction through the channel 8 and pneumatic 38 becomes too strong. However, to prevent the closing of the port 39, except at 115 a predetermined time, the leaf of the pneumatic is provided with a flat spring 45, the free end of which is adapted to bear against an adjustable stop, such as the screw 45^a.

Secured to the upper wall of the main suction channel 8, is the valve box 46, to which, in turn, is suitably secured, the snare drum 2. This valve box is similar in construction to the one shown and described in my pending application filed November 20, 1912, Se- 120 125 130

rial Number 732,446, and has fixed to one end a pneumatic 47, to the leaf of which is fastened the hammer 48, adapted to impinge against the drum head when the pneumatic 47 is depressed or collapsed, and which carries at its other end a pneumatic 49, to the leaf of which is fastened a damper 50, adapted to rest upon the snare strings 51, when the hammer 48 stops vibrating, to prevent a continued humming of the drum after playing thereon has ceased. The interior of the valve box 46 is divided into two chests 52 and 53 by a transverse partition 54, and a constant vacuum is maintained within the chest 52, through a comparatively large port 55, which registers with a similar port formed in the top wall of the main suction chamber 8.

Mounted vertically in each chest 52 and 53 is a valve stem 56, carrying at its upper end a valve 57, which works in a chamber 59, one end of which communicates with the interior of the chest, and the other end with the outside air, through vents 60. The valve chamber above the chest 52, is provided with a port 61, leading to the interior of the chest 53, and the valve chamber above the chest 53, has a port 62 leading to the interior of the pneumatic 47.

The lower end of the stem 56 is fastened in any suitable manner to a flexible diaphragm 63, secured in place over a suitable chamber 64. Leading from the diaphragm chamber 64 of the chest 53 is a port 65, which terminates in a passage 66, having two diameters, the smaller of which leads to the interior of the chest 53, and the larger to the outside air. The inner end of the passage is controlled by a valve 67, on the stem 68, on which is also fastened a valve 69, which controls the outer end of the passage 66. These valves 67 and 69 are actuated by an arm 70, secured to the leaf of the pneumatic 47 and slidably mounted on the stem 68, between a washer 71 and the upper end of a lever 72, pivotally mounted to the end of the valve box 46, and fixed to the valve 69. A suitable spring 72 is provided for normally holding the lever 72 away from the box 46, in which position the inner end of the passage 66 will be closed by valve 67, but its outer end will be open to the outside air. A hose or tube 74 leads from the valve chamber 53 to the pneumatic 49, which carries the damper piece 50. Also mounted to the main suction channel 8, is a standard 75, to the upper end of which is fixed a horizontally extending arm 76, on the end of which is hung the triangle 3. As shown most clearly in Fig. 17, the standard 75 has fastened thereto a valve box 77, which in turn has fixed to its underside a pneumatic 78, to the leaf of which is fastened the striker 79 for sounding the triangle. A port 80 leads from the interior of the valve box 77 to an opening

81, formed in the upper wall of the channel 8, whereby the suction of air through said channel will create a suction within the valve box 77 is a chamber 82, over which is placed a diaphragm 83, and to which is suitably fastened a vertically disposed valve stem 84, carrying near its upper end a valve 85, working in a chamber 86 formed in the top wall of the valve box. From one side of the chamber 86 a port 87 leads to the outer air and from its other side a port 88 leads to the interior of the pneumatic 78. A port 89 leads from the chamber 82 under the diaphragm 83 through the standard 75 and is connected to a hose 90.

Preferably at a point directly behind the valve box 77, on the suction chamber 8, is mounted a support 91, to which is secured the cymbal 4. As most clearly shown in Fig. 18, the support 91 has fastened to its front edge a pneumatic 92, to the leaf of which is fixed an upwardly extending arm 93 and which carries at its upper end a suitable striking member 94 adapted to impinge against the cymbal when the pneumatic 92 is deflated. Leading from the interior of the pneumatic 92 to one side of the support 91, is a port 95, and from which a hose 96 leads to the valve mechanism for controlling the pneumatic 92, as will be presently described.

At a point below the large drum 5, the main suction channel 8, has securely fastened to its underside a block 97 to which, in turn, is fastened a shelf 98, which extends beyond the front side of the main suction channel 8, and on which extending portion is mounted an elongated valve box 99. As shown in Fig. 15 the shelf 98 is hollow and a passageway 100 connects its interior with the suction channel 8, whereby air will be exhausted from said shelf by the suction through said channel, and also from the interior of the valve box 99, by way of an opening 101, leading from the interior of the valve box to that of the shelf.

Fixed to the front wall of the valve box 99, are a pair of pneumatics 102, arranged on opposite sides of a larger pneumatic 103. A drum hammer 104 is fastened to the leaf of each pneumatic 102, and a similar, except slightly larger drum hammer 105, is fastened to the leaf of the pneumatic 103. The three pneumatics above mentioned are inflated and deflated independently of one another, the two hammers 104, fixed to the pneumatics 102, being adapted to alternately impinge against the drum head to produce the soundings of a kettle drum, while the hammer 105 carried by the pneumatic 103 will strike the drum head with greater force, owing to its greater weight and correspondingly larger pneumatic, than the hammers 104, and will produce a base drum-note. Arranged within the valve box 99 in line 130

with each of the pneumatics 102 and pneumatic 103 is a vertical valve stem 106, fitted at its lower end to a diaphragm 107, mounted upon a chamber 108. The valve stem 106 is also provided with a valve 109, adapted to work within a chamber 110, having a port 111 leading to the interior of the valve box 99, and a port 112 leading to a horizontally extending groove 113, which, in turn, communicates at each end with the outside air. The outside air is normally admitted to the interior of the pneumatic by means of a passage 114, leading from the chamber 110. Leading from the chamber 108 beneath the diaphragm 107, there is a port 115, to which is connected one end of a hose 116, the other end of which is connected to an intermediate valve box, which will be presently described.

Extending within the shelf 98 there is an arm 117, the outer end of which is bent upwardly to form a handle 118 and the inner end of which is provided with a valve member 119, adapted, when the handle 118, is moved to one side, to raise the valve 119, and close the passage 100, thereby cutting off communication between the interior of the valve box 99, and the main suction chamber 8, and consequently discontinuing any further sounding of the instruments controlled by the valve box 99.

As heretofore stated, Fig. 15 is a section taken through the pneumatic for producing the base drum notes, its controlling valve and air ports or passage, and as an exact duplication of the valve and arrangement of ports above described, is provided within the valve box 99 for each of the pneumatics 102, it is not thought necessary to further describe these parts. Also arranged within the end of the valve box 99, adjacent to the controlling valve box 24, is a fourth valve and arrangement of air ports for controlling the cymbal pneumatic 92, exactly the same in every respect to the valve and air ports controlling the base and kettle drum pneumatics, except that instead of the port which corresponds to the port 114, shown in Fig. 15, being connected directly to the pneumatic 92, it is connected thereto through the hose 96, heretofore mentioned.

Secured to the upper side of the suction channel 8, at a point suitably removed from the valve box 99, there is an intermediate valve box 120, the interior of which is connected with the suction channel 8, through suitable ports 121, and consequently air will be constantly exhausted from the interior of the valve box 120, by the suction of air through the channel 8.

Arranged vertically with the valve box 120 are five controlling valves as at 122, 123, 124, 125 and 126, in Fig. 22. As will be noted these valves are arranged so that no two of them will be in alinement with a line drawn transversely across the valve box and which

is for the purpose of permitting ports or passages to lead from the valves to either the front or back of the valve box in parallel relation, but without interfering with one another. The five valves are identical in structure, each comprising a stem 127, fastened at its lower end to a diaphragm 128, mounted over a chamber 129, and extending upwardly through openings 130, formed through the top board of the valve box, and being guided at their extreme upper ends by a cover 131. Fixed to the valve stems 127, at points above and below the top board of the valve box are valves 132, larger in diameter than that of the openings 130, the distance between the valves being slightly greater than the thickness of the said top board of the valve box, whereby when one of the valves is seated over the adjacent end of the opening 130, the other valve will rest a slight distance away from the other end of the opening so that no matter whether the valve stems 127 are raised or lowered, only one end of the openings 130, will be closed, the other end remaining open. As most clearly shown in Figs. 23 and 24, the cover 131 is raised above the top board of the valve box 120, so as to form a space 133 therebetween, and which space opens to the outer air at both ends of the valve box. Entering the bottom board of the valve box 120, from the rear side thereof are ports 134, one leading to each of the chambers 129, below the diaphragm 128, and thence to the front wall of the valve box, at which point each port 134 has inserted therein a bleed 135. These bleeds 135 communicate with a groove 136 formed in a block 137, secured to the front wall of the valve box with its groove 136 opposite the bleeds 135. As shown in Fig. 22 the groove 136 is connected with the interior of the valve box 120 and consequently with the exhaust by means of the passages 136 shown by dotted lines. The cover 131 effectively serves to prevent dust from settling upon the valves 132, but at the same time admits the outer air thereto. Leading from the opening 130 of the controlling valves 124, 125 and 126, to the front of the valve box 120 is a port 138, while leading from the opening 130 of the controlling valves 122 and 123 to the rear of the valve box is a similar port 139. The port 138 leading from the controlling valve 125, communicates with a branch port 140, the mouth of which leads to the front of the valve box slightly above the mouth of the port 138.

Connected to the port 138 of the controlling valve 125, is the hose 116, which leads to the port 115, of the valve for controlling the base drum pneumatic 103, while leading from the branch port 140 is a hose 141, which is connected at its other end to the port leading to the diaphragm chamber of the 130

cymbal controlling valve. The cymbal and base drum notes are sounded simultaneously, hence their valve mechanism communicates with the controlling valve 125. From the 5 ports 138 of the valves 124 and 126, lead hose 142, which are connected at their other ends to the ports leading from the dia-phragm chambers of the valves for controlling the kettle drum pneumatics 102. Connected to the port 139 of the controlling 10 valve 122, is a hose 143 and connected to port 139 of the valve 123 is another hose 144, both of which hose lead to a cut-off box 145, carried by the main suction chamber 8. As most clearly shown in Figs. 5, 6 and 7, the interior of this cut-off box 145 is divided into two compartments by means of a central partition 146, in each of which is placed a slide valve block as at 147 and 15 148, held in close contact with the bottom of the cut-off box by means of flat springs 149, and provided with suitable operating handles 150. Entering from one side of the cut-off box 145 and leading to the compartment 20 occupied by the valve block 148 is a port 151, while entering from the same side of the box 145 and leading to the compartment occupied by the valve block 147 is another port 152. Also entering the cut-off box 25 from its opposite side are ports 153 and 154, the port 153 leading to a point to close proximity to the inner end of the port 151, under the valve block 148, and the port 154 leading to a point close to the inner end of the port 152 under the valve block 147, the 30 underside of the valve blocks 147 and 148 being provided with a groove 155, sufficient in length to span the inner ends of the opposed ports when the valve blocks are in the position shown by block 147, in Fig. 6, and form a continuation of the ports, but which will break connection between the ports when moved to the position shown by block 148, in Figs. 6 and 7.

40 The hose 143 and 144 from the intermediate valve box 120 connect with the ports 152 and 151 respectively, while connected to the port 153 is the hose 90, which leads to the valve mechanism for controlling the sounding of the triangle 3, and connected to the port 154 is a hose 156, which leads to the valve mechanism for playing the snare drum 2. It will thus be seen that by means 45 of the cut-off box 145, the sounding of the snare drum 2 or triangle 3 may be readily discontinued whenever desired, notwithstanding that the player paper may be provided with perforations for the playing of these two instruments. Connected to each 50 of the ports 134 at the rear of the intermediate valve box 120 is a hose 157, all of which lead to the tracker-bar or other playing device of the instrument.

55 Mounted horizontally within the casing 1, preferably below the suction channel 8,

there is a wind channel 158, and from which the necessary air pressure to sound the flute tubes 6 and violin tubes 7 is supplied. This wind channel 158, as best shown in Fig. 16, is formed with two separate compartments 70 159 and 160, by a vertically and centrally disposed partition 161, running the entire length of the channel. Formed in the top board of the channel 158, near its front edge are a plurality of pockets 162 in which the lower ends of the graduated series of flute tubes 6 are adapted to fit snugly, while also formed in the top board of the channel, near its rear edge are a plurality of similar pockets 75 163, arranged in a row parallel to the row of pockets 162, into which pockets 163 the graduated violin tubes 7 are mounted. Leading from each of the pockets 162 and 163 is a port 164 and 165 respectively. The ports 164 leading from the pockets 162 communicating with the compartment 160 and those leading from the pockets 163 communicating with the compartment 159. The entrance of each of these ports from its respective compartment is controlled by means 80 of a valve 166, fixed upon a slide stem 167, the inner ends of which are mounted in guide holes formed in opposite faces of the partition 161, their outer end passing through the front and rear walls of the 85 channel 158 and being provided with a leather washer or bumper 168. Coiled around each of the valve stems 167 between the valves 166 and the adjacent face of the partition 161 is a spring 167^a, the tension of which normally keeps the valve 166 in closure with the entrance of the ports 165 and 164, thereby preventing any air which may be in the compartments 159 and 160 from entering said ports. To provide for the 90 opening of the entrance to the ports 165 and 164 I attach to the front and rear walls of the channel 158 a plurality of pneumatics 169, one for each of the valves 166, and to the leaves of each pneumatic 169 is fastened 95 a striker-arm 170, the ends of which are adapted to impinge against the bumper washer 168 when the pneumatic, to which the striker arm is secured, is deflated and to then force the valve stem inwardly against 100 the tension of its spring and consequently move the valve 166 away from the entrance way to its adjacent port. Leading from each pair of oppositely disposed pneumatics 169 is a port 171, which communicates with 105 another port 172, formed in a strip 173, fastened to the underside of the channel 158, and extending the full length of the same. From the ports 171, hose 174 may lead to any desired means for controlling the pneumatics 169.

110 To the end of the casing 1 adjacent to the snare drum 2, is mounted a rectangular chest comprising a frame 175, having front and back panels 176. Connected to one 115

120 125 130 135 140 145 150 155 160 165 170 175 180

side of the frame 175 is one end of a transversely extending strip 177, its other end being connected to the upper end of a vertically extending strip 178, the lower end of which latter strip 178 being secured to the bottom of the frame 175. Connected to the other side of the frame 175, is a transverse strip 179, its inner end being connected to the strip 178, about midway between its ends, while extending between the strip 179 and the bottom of the frame 175 is another strip 180, arranged parallel to the strip 178, and connected to the strip 179 at a point an equal distance from its ends. 5 All of the strips above described are of the same height as that of the strips forming the main frame 175, so that when the panels 176 are secured in place over the frame 175, separate compartments 181, 182, 183 and 184 will be formed within the chest. 10 Securely fastened to the front panel 176 of the chest 175, opposite the compartment 181, is a chest 185, the upper end of said chest being closed by a block 186, provided with 15 a passage 187, leading from its upper edge to a registering opening 188, formed in the front panel 176 of the chest 175, immediately below the strip 177. Said front panel of the chest 175 is also provided with 20 an opening 189, which establishes communication between the interior of the chest 185 and the compartment 182 of the chest 175. Also fastened to the front panel 176 is a valve chest 190, located opposite the compartments 183 and 184, the upper end of which 25 extending above the strip 179 and between which strip 179 and the upper end of the valve chest, the front panel 176 is provided with an opening 191, which connects the 30 interior of the valve chest 190, with the compartment 182. Leading from the compartment 183 to the interior of the valve chest 190 is an opening 192, while a similar opening 193 also leads into the chest 190, from 35 the compartment 184. Suitably mounted to the front panel 176 of the frame 175, immediately below the valve chest 190 is the end of the wind channel 158, so positioned that its partition 161 will be directly 40 opposite the strip 180, and thereby bring the compartments 159 and 160 in alignment with compartments 183 and 184 respectively, communication between the compartments 183 and 159 being had through an opening 194, while communication between the compartments 184 and 160 is formed through 45 a similar opening 195. As most clearly shown in Fig. 20, the end of the main suction channel 8 rests upon the upper edge 50 of the block 186, of the chest 185, the bottom wall of said channel 8 being provided with an opening 196, which registers with the opening 187 of the block 186.

Secured to the front panel 176, above the 55 suction channel 8, there is a large reservoir

bellows 197, the interior of which is connected with the compartment 182, through a comparatively large opening 198, formed in the front panel 176.

The leaf of the bellows 197 is guided in a 70 suitable frame 199, and compression springs 200 are interposed between said leaf and guiding frame, as shown in Fig. 1. The leaf of the bellows 197 is provided with a 75 relief valve 201, adapted to be opened by a stop 202 secured to the frame 199, when said relief valve 201 comes in contact therewith, thereby preventing pressure in the reservoir bellows from exceeding a predetermined amount. 80

Leading from the lower end of the compartment 181 are a plurality of hose or conduits 203, which connect with the main suction feeder or vacuum pump (not shown) of the instrument, while connected to the 85 bottom of the chest 185, are similar hose 204 which lead to the main pressure feeder (not shown).

The means I employ for admitting air into the compartments of the wind channel 90 158, during the period of time in which the violin or flute tubes are to be sounded comprise valves 205 positioned within the valve chest 190, adjacent the openings 192 and 193, and slidably mounted upon guide 95 rods 206. Each valve 205 is provided with an operating arm 205^a which extends through the chest 190, and is connected at its outer end, in any suitable manner, to the leaf of a pneumatic 207, carried by the 100 chest 190, there being two of these pneumatics 207, one for each of the valves 205, as shown in Fig. 19. Leading from the interior of each of the pneumatics 207, is a port 208, and connected to each port 208, 105 is a hose 209, which in turn leads to automatic controlling valve boxes 210, fastened to the underside of the suction channel 8, and which are identically the same in structure and function as the controlling valve 110 box 24. From each of the boxes 210, lead hose 211, the other ends of which are connected to the tracker-bar.

In order to prevent any air which may 115 remain in the wind channel 158, after the valves 205 are closed, from sounding the flute or violin tubes, I provide each of the compartments 159 and 160 with an exhaust port 212, each port 212 adapted to be opened and closed by means of a valve 213, carried by the leaf of a pneumatic 214, the interior of which is connected to the port 208 by way of a hose 215 and port 216.

In operation, the vacuum and pressure pumps, which may be driven by an electric 125 motor, (not shown), are set in motion, the vacuum pump creating a suction throughout the main suction channel 8, and all of the various valve and cutoff boxes in communication therewith, by way of the openings 130

196, 188, passage 187 and compartment 181, and a vacuum is consequently maintained in these parts of my invention. From the pressure pump air first enters the chest 185, 5 and then passes into the compartment 182, through the opening 189, and into the reservoir bellows 197, inflating the same against the tension of the compression springs 200. Air also enters the valve chest 190 through 10 openings 191, the purpose of the reservoir bellows 197, being to maintain an even steady pressure of the wind for the organ pipes and to cushion the pulsations of the air caused by the strokes of the pressure 15 pump.

Normally the valves 122, 123, 124, 125 and 20 126 of the intermediate valve box 120, rest in the position shown in Figs. 23 and 24, the vacuum within the valve box 120 permitting pressure of the outer air under the cover 131 upon the valves 132, to hold these valves down and in closure with the upper end of the ports 130. When the valves are in this 25 position, the lower ends of the ports 130 will be open and air will be consequently exhausted from all of the hose connected to the ports 138 as well as the hose connected to the branch port 140. Likewise air will be exhausted from the diaphragm chambers to 30 which these hose lead.

Now say, for instance, that a perforation in the note sheet registers with an opening in the tracker-bar to which the hose 157, leading from the port 134, of the diaphragm 35 chamber 129 of the valve 125, is connected. As soon as this occurs, air will be admitted to the port 134, through the hose 157 and as this air enters the diaphragm chamber 129 faster than it can be drawn through the 40 bleed 135 by the exhaust, it will soon overcome the pressure of the outer air upon the upper valve 132, and consequently flex the diaphragm 128 upwardly, thereby raising the valve stem 127 and bringing the lower 45 valve 132 in closure with the lower end of the port 130, at the same time raising the upper valve 132 away from the upper end of the port 130. This will permit the outer air to enter the port 138 and branch port 50 140, and thence by way of hose 116 and hose 141 to the diaphragm chambers 108, of the controlling valves for the bass drum, and cymbal pneumatics, which two instruments 55 are sounded simultaneously as heretofore stated. The valves for controlling the operation of the pneumatics for these two instruments, as well as those for controlling the pneumatics of the other different instruments all rest normally in a position 60 as shown, for instance, in Fig. 15, in which position, the vacuum on both sides of the diaphragm will permit the outer air to depress the controlling valves, and thereby allow said outer air to enter the interior of the pneumatics to keep the same

distended. In this particular instance outer air will enter the pneumatic 103 through the passage 113, port 112, chamber 110 and port 114. Now as soon as the outer air is admitted to the diaphragm chamber 108, as 70 above described, the vacuum within the valve box 99 will allow the pressure under the diaphragm 107 to overcome the downward pressure of the outer air upon the valve 109, and consequently the diaphragm 107 will be 75 moved upwardly and the valve 109 will close communication between the chamber 110 and the outer air, and open communication between the interior of the valve box 99 and the chamber 110, whereby the suction in the 80 main suction channel 8, will exhaust air from the interior of the pneumatics 103 by way of the port 114, chamber 110, ports 111 and 101, hollow shelf 98, and passage 100, thereby allowing the pressure of the outside 85 air to collapse or deflate the pneumatics 103, and its hammer 105 to impinge against the head of drum 5. Then as soon as the admittance of air to the port 134, is cut off, as by an unperforated part of the player paper, 90 the valves will return to their normal positions and the outer air will again be admitted to the pneumatics 103, and its hammer moved away from the drum head.

The action of the valves for controlling 95 the pneumatics of the cymbal, triangle and for sounding the kettle drum notes on the drum 5, is exactly similar to the action of the valve for controlling the pneumatics 103 as above described. The operation of the 100 valves within the valve box 46, however, is somewhat different, since the beatings of the snare drum 2 must be considerably more rapid than that of the other instruments and its pneumatic 47 must be inflated a 105 number of times while a single perforation in the player paper passes over the opening in the tracker-bar to which the hose 157 is connected. When this occurs and air is admitted to the diaphragm chamber 129, 110 below the diaphragm 128 of the controlling valve 123, thereby raising this valve, and opening its port 139 to the outer air—consequently the outer air will enter the hose 143, pass through the ports 152 and 154 of the 115 cut-off box 145, providing the valve block 147 is in the position shown in Fig. 6, and thence into the hose 156 to the chamber 64 below the diaphragm 63. As there is a 120 vacuum within the chest 52, the pressure of the outer air under the diaphragm will flex the same upwardly, thereby closing the vent 60, and opening the port 61, leading to the chest 53, and thus allowing the suction of air through the channel 8 to withdraw air 125 from the chest 53. In so doing it connects the hose 74 with the chest 53, so that air will be drawn out of the pneumatic 49, to deflate the same and raise the damper 50, off the snare strings of the drum 2. Likewise the 130

outer air entering the diaphragm chamber 64, of the chest 53, though the port 65, and passage 66, will raise the diaphragm above said chamber 64 and close the vent 60 and connect the port 62, with the channel 8, whereby the suction therethrough will draw air out of the pneumatic 47 and cause its hammer 48 to strike the drum 2. In so doing, the end of the arm 70 will strike the upper end of the lever 72, thereby closing the valve 69 over the outer end of the passage 66, and moving the valve 67 away from the inner end of the said passage, thereby connecting the port 65, with the channel 8, and allowing air to be drawn from under the diaphragm. As soon as this is done the outer air will depress the valve of chest 53, and allow the outer air to again enter the pneumatic 47 to deflate the same and move its hammer 48 away from the drum. At the same time the arm 70, will strike the nut 71, thereby moving the valve stem 68, outwardly to cause its valves 69 and 67 to open the outer end of the passage 66 and close its inner end, respectively. Then as soon as sufficient air has entered the diaphragm chamber 64, of the chest 53, to overcome the downward pressure upon the valve 57, said valve will again be raised to close the vent 60, and connect the port 62 with the chest 52, and thence with the channel so that the exhaust therethrough will again collapse the pneumatic 47. It will thus be seen that this pneumatic 47, will be intermittently inflated and deflated as long as the valve within the chest 52 is kept raised by the admission of air through the hose 156.

If it is desired at any time to discontinue the playing of the different instruments actuated by the valves of the valve box 99, it may easily be done by simply swinging the handle 118 of the rod 117 to one side, which will raise the valve 119 in closure with the lower end of the passage 100. By means of the cut-off box 145 the playing of the snare drum and triangle may also be discontinued, as desired, by pushing in the valve blocks 147 and 148 to break communication between the ports formed through said cut-off box.

As shown in Fig. 12, the valve 14 is normally kept raised off the port 10, and air being exhausted from the channel 8 has free passage through the ports 10, 11, into the compartment 181. When the valve 14 is in this position the pneumatic 17 is held distended by means of the outer air entering the port 25 of the control valve box 24, hose 23, block 12 and hose 20. However, when the notes of the musical composition being played are to be sounded softly, a perforation to the note sheet will register with an opening in the tracker-bar to which the hose 32, connected with the interior of the pneumatic 28, leads and when this occurs air will

be admitted to said pneumatic 28, which will inflate this pneumatic and shift the lever 33, to move the valve block 34, until its passage 35 covers both the port 36 and the adjacent end of port 25, thereby connecting the interior of the pneumatic 17, with the channel 8. Consequently air will be exhausted from said pneumatic 17, and the outer air will deflate the same and its arm 18 will press the bent wire lever 13, downward, and the valve 14 will be, in turn, lowered into closure with the port 10, when the tension of spring 45, will regulate the admission of air through ports 39, 41. When this occurs the suction of air from the channel 8 will be retarded since it can pass therefrom through pneumatic 38 only, and the pneumatics for playing the various instruments will be deflated with correspondingly less force.

In further explanation of the operation of the pneumatics 28 and 29, it will be understood that air is exhausted from the pneumatics through the bleeds 30, which will tend to keep both of the pneumatics collapsed. However, as during the time when the notes of the various instruments are to be sounded loudly, an opening in the tracker bar to which the hose 32 of the pneumatics 29 leads will be uncovered by a perforation in the note sheet. Obviously this will admit outside air through the tracker bar and hose 32 to the pneumatic 29, but not to the pneumatic 28, and consequently air entering the pneumatic 29 will inflate this one while pneumatic 28 will remain closed. Then when the notes of the instrument are to be subdued, an unperforated part of the note sheet will pass over the opening in the tracker bar for the hose of the pneumatic 29, thereby shutting off the outside air to this hose and at the same time a perforation in the note sheet will register with the openings provided in the tracker bar for the hose of the pneumatic 28, thereby admitting air to this hose and reversing the action of the pneumatics 28 and 29.

The valves 205 for controlling the admission of air from the valve box 190 into the compartments 159 and 160 of the wind channel 158 normally rest in closure with the ports 193, as shown in Fig. 11, with the valves 213 raised off the exhaust ports 212. The valves are held in this position by the outer air entering the ports 208 and 216 by way of the hose 209 from the controlling valve boxes 210, which as above stated, are identically the same in every respect as the box 24. It will therefore be understood that when a perforation in the note sheet, which determines the period of time during which the flute or violin tubes are to be sounded registers with the proper opening in the tracker-bar, air will be admitted to the proper hose 211, and the valve blocks of 130

the boxes 210, will be shifted to connect the hose 209 with the suction channel 8, thereby exhausting air from the pneumatics 207 and 214, so that the pressure of the outside air will deflate the same, the pneumatic 207 moving the valves away from the openings 193 and admitting air from the chest 190 into the compartments of the wind channel. At the same time the exhaust ports 212 will 10 be closed by the valve 213. From the compartments 159 and 160 air is admitted into the proper flute or violin tubes by means of the valves 166 operated by the pneumatics 169 in a manner as heretofore described.

15 Having thus fully described my invention, what I claim as new and desire to secure by Letters Patent is—

1. In a pneumatically actuated musical instrument, including a casing, a main suction channel mounted within said casing, a plurality of valve boxes mounted upon and communicating with said suction channel, pneumatics connected to said valve boxes, diaphragm actuated valves within the valve 25 boxes, and being normally subject to the pressure of the outside air and held in position to admit said outside air to the interior of said pneumatic, a trackerbar, valve between said bar and pneumatics for each of 30 said diaphragm actuated valves for admitting air beneath the diaphragm to overcome the pressure of the outer air and to cause the same to operate for disconnecting the interior of the pneumatic from the outer air and 35 connecting it to the interior of the valve box.

2. In a pneumatically actuated musical instrument, including a casing, a main suction channel mounted within said casing, a 40 plurality of valve boxes mounted upon and communicating with said suction channel, pneumatics carried by said valve boxes, diaphragm actuated valves within the valve boxes and being normally subject to the 45 pressure of the outside air and held in position to admit said outside air to the interior of said pneumatic, a tracker bar, a pneumatically controlled valve between said bar and pneumatic for each of said diaphragm 50 actuated valves for admitting air beneath the same to overcome the pressure of the outer air and to cause the same to operate for disconnecting the interior of the pneumatic from the outer air and connecting it 55 to the interior of the valve box.

3. In a pneumatically actuated musical instrument, including a casing, a main suction channel mounted within said casing, a plurality of valve boxes mounted upon and 60 communicating with said suction channel, pneumatics carried by said valve boxes, valves within the valve boxes, and being normally subject to the pressure of the outside air and held in position to admit said 65 outside air to the interior of said pneumatic,

a trackerbar, a valve between said bar and pneumatic for each of said diaphragm actuated valves for admitting air beneath the diaphragm to overcome the pressure of the outer air and to cause the same to operate 70 for disconnecting the interior of the pneumatic from the outer air and connecting it to the interior of the valve box, and cut-off devices operated by hand for disconnecting the intermediate valves from the diaphragm actuated valves. 75

4. In a pneumatic self-playing musical instrument, a casing, a main suction channel detachably mounted within said casing and from which air is continuously being 80 drawn, a plurality of valve boxes mounted upon and communicating directly with said channel, pneumatics connected to said valve boxes, valves arranged within the same for opening and closing a passage between the 85 interior of the valve box and its pneumatics, and also between the interior of the pneumatic and the outside air, a controlling valve box also mounted upon and communicating with said channel, a plurality of valves arranged therein for controlling the operation 90 of the first mentioned valves, tubes connecting the first to the last mentioned valves, means arranged with respect to certain of said tubes for disconnecting the valves at 95 the ends thereof, and additional means for disconnecting certain other of the first mentioned valves from the suction channel, striking members carried by said pneumatics, and musical instruments carried by said 100 channel in positions to be played upon by said striking members.

5. In a pneumatic self-playing musical instrument, a casing, a main suction channel mounted within said casing, a plurality of individual valve boxes mounted upon and communicating directly with said suction channel, pneumatics carried by said valve boxes, valves arranged within the valve boxes and which are normally subject to the 105 pressure of the outside air and held in position to admit said outside air to the interior of said pneumatics, diaphragms connected to and adapted to actuate the valves, a governing valve for each of said diaphragm 110 actuated valves for admitting air beneath said diaphragms to overcome the pressure of the outside air and to cause the diaphragm actuated valves to operate for disconnecting the interior of the pneumatics 115 from the outside air and connecting the same with the interior of its valve box, and cut-off devices operated by hand for disconnecting the governing valves from the diaphragm actuated valves. 120

6. In a pneumatic self-playing musical instrument, a main suction channel, a plurality of different musical instruments carried by said channel, valves and means controlled thereby for playing upon said instruments, 130

said suction channel having a transverse partition therein separating openings formed in the channel on opposite sides thereof, a box positioned on the channel to cover said openings, a lever journaled in said box and a valve carried by said lever and positioned to form a closure for one of said openings, a spring connected to said lever for normally holding the same raised with its valve off 10 the said opening, a pneumatic, an arm carried thereby adapted to impinge against the lever when said pneumatic is collapsed to lower the same and close the valve to discontinue the flow of air through said openings,

a valve box secured to and connecting with 15 said channel, a pair of pneumatics arranged therein, and a valve operated thereby for controlling the aforesaid arm carrying pneumatic.

In witness whereof, I have hereunto sub- 20 scribed my name this 6th day of February 1913, in the presence of two subscribing witnesses.

PEDER WIGGEN.
